UNITED STATES PATENT OFFICE

2,615,750

BOTTLE CARRIER

William L. O'Sullivan, Milwaukee, Wis.

Application September 3, 1948, Serial No. 47,739

1 Claim. (Cl. 294—87.28)

1

This invention relates to a carrier for bottles for beverages and the like which carrier is particularly adapted for carrying bottles from the retail trade to the ultimate consumer.

It is a main object of the invention to provide a bottle carrier composed of cardboard and the like so folded as to provide a convenient carrying means needed to transport bottles from one place to another.

It is a further object of my invention to provide a bottle carrier which can be applied to bottles while they are still in the original case and adapted to lift the bottles out of the usual case without further manipulation.

Another object of the invention lies in the provision of a bottle carrier arranged to permit the convenient packaging of bottles with a minimum of handling thereof thereby lessening the labor required to arrange such bottles in saleable groups.

Further objects of the invention, not specifically mentioned here, will become apparent from the detailed description and the claim which follows reference being had to the accompanying drawings in which:

Figure 1 is a perspective view of one embodiment of my new bottle carrier showing the bottle carrier affixed to six beverage bottles;

Figure 2 is a perspective view of my improved bottle carrier showing one form of arranging it for convenient shipment;

Figure 3 is a top plane view of the blank form in which my improved bottle carrier is manufactured;

Figure 4 is a longitudinal sectional view on the line 4—4 of Figure 3;

Figure 5 illustrates my improved bottle carrier in section in position to be placed over a plurality of beverage bottles arranged in their normal vertical position as when they are in the original case;

Figure 6 is a view illustrating my improved bottle carrier in section being moved downwardly upon the bottles;

Figure 7 is a view showing the bottle carrier in section being lifted upwardly and illustrating how the parts of the carrier cooperate with the bottles to maintain a tight hold;

Figure 8 is a detailed sectional view showing the cooperation between the bottle carrier and each individual bottle;

Figure 9 is a detailed sectional view showing how the improved bottle carrier cooperates with a bottle having its cap removed.

In the normal handling of beverage bottles from the sources of supply to the consumers, the

2

bottler or shipper normally delivers the bottled goods to the retailer in case lots, each case having twelve or twenty-four bottles. The retailer then ordinarily sells the bottled goods to the ultimate consumer in groups of six bottles. In order to package the goods for the consumer, the bottles must be removed from the case and must be placed in suitable packages or containers. My improved device is merely slipped over the bottles in their normal vertical position in the case, the carrier is lifted, and there is instantly available a convenient package to be handed to the consumer so that he may carry it on his way.

The preferred embodiment of my bottle carrier 1 is made from a flat sheet of cardboard and is provided with a plurality of bottle embracing holes 2 and a hand hole 3. Initially, the cardboard is a flat sheet with the bottle holes 2 extending therethrough. The hand hole 3 is formed by partially cutting the cardboard as at 4 to form a three-sided ear 5 and folding the ear back as at 6. The cardboard is folded back upon itself at folding locations 7, 8, 9, 10 and 11 to form a vertically arranged carrying portion 12, an upper bottle neck embracing portion 13 and a lower bottle neck embracing portion 14.

The diameters 15 of the holes 2 are proportioned slightly larger than the overall diameter of the cap 16 and the upper neck portion 17 of the bottles 18 with which the bottle carrier is to be used. The distance 19 between adjacent holes 2 is arranged to coincide with the normal distance between bottles in the case. Each of the inner series of holes 2 is separated from its inner adjacent folding locations 8, 9 by the distance 20 which is approximately one-half of the distance between adjacent rows of bottles in the case. Thus when the upper bottle embracing sections 13 are in a flat plane (see Figure 6), the distance 21 between the holes 2 is approximately equal to the distance between adjacent rows of bottles.

In assembling my improved bottle carrier, the blank is folded downwardly, Figure 3, at the folding location 7 between the two halves of section 12. The outer portions 13 and 14 of the two halves of the blank are then bent upwardly at the folding locations 8 and 9 between sections 12 and 13. The outer portions 14 are then bent downwardly at the folding locations 16 and 11 between sections 13 and 14. The earlike portions 5 formed by the cuts 4 are then bent together along the folding locations 6 so as to form the carrying hand hole 3. The resulting assembly appears in section in Figure 5.

The bottle carrier is secured to the bottles 18

by placing it over the bottles as appears in Figure 5, then by pressing it downwardly until the bottle embracing portions 13 and 14 approach a horizontal plane as appears in the solid line position Figure 6, by continuing downwardly over the bottles as appears in the dotted line portion in Figure 6 until the upper flap 13 is below the cap 16 of the bottle 18 and then by lifting upwardly as appears in Figure 7. The holes 2 in the upper flap 13 on their inward edge grip under the edge of the cap 16 and on their outer edge grip the neck shoulder 17 of the bottle. The lower holes 2 in the lower bottle embracing flap 14 rest around the neck of the bottles and cooperate in holding the bottles in proper vertical and aligned position.

Figure 9 illustrates how the bottle carrier cooperates with the neck portion of a bottle when the cap is removed.

From the foregoing it will be apparent that my invention is possessed of many advantages. It affords a cheap, high quality carrier for carrying bottles, which carrier can be shipped conveniently to the retailer in flat blank form. The bottle carrier may be conveniently and easily assembled and may be conveniently and easily affixed to the bottles.

While I have chosen to show my invention by illustrating and describing a preferred embodiment, I have done so by way of example only, as there are modifications and adaptations which will become apparent to one skilled in the art within the teachings of the invention. Having thus complied with the statutes and having shown and described a preferred embodiment of my invention, what I consider new and desire to have protected by Letters Patent is pointed out in the appended claim.

I claim:

A device for supporting an article having, in downwardly progressive vertical order, an enlarged portion, a restricting portion, a second enlarged portion, a second restricting portion and a neck portion, said device comprising a blank cut and scored from sheet material to form a suspending part and an article engaging part

with a fold line therebetween, said article engaging part comprising a member extending integrally outwardly from the suspending part and foldable with respect thereto and a second member having a free end foldable under the first named member and integral with the outer end of the first named member, the free end of said second member being independent of said suspending part, said first named member having a large article receiving aperture adapted to pass over the two enlarged portions of the article, every diameter of said aperture being larger than the diameter of the two enlarged portions of the article when said outwardly extending member is in a horizontal position and the lesser diameter of the horizontal projection of said aperture being smaller than the diameter of the two enlarged portions of the article when the outwardly extending member is in an angular position whereby an inner portion of the circumference of said aperture embraces the article beneath said first enlarged portion and an outer part of the circumference of the said aperture embraces the second restricted portion of the article beneath said second enlarged portion in suspending an article from said first part, and the said second named member having a large article receiving aperture adapted to pass over the two enlarged portions and the neck portion of the article, every diameter of said aperture being larger than the diameter of the two enlarged portions of the article, so that said aperture embraces the neck portion of said article to maintain it in substantially vertical alignment.

WILLIAM L. O'SULLIVAN.
